ROCK DRILL

Mervin Chester Huffman, Claremont, N. H., assignor to Sullivan Machinery Company, a corporation of Massachusetts

Application March 6, 1934, Serial No. 714,312

15 Claims. (Cl. 121—9)

This invention relates to rock drilling mechanisms, and more particularly to improvements in the feeding and guiding means for a rock drill of the mounted hammer type.

5 An object of this invention is to provide an improved rock drilling mechanism. Another object is to provide an improved feeding means for a rock drill of the mounted, self-feeding, hammer type. A further object is to provide an improved supporting and guiding structure for a rock drill. Yet another object is to provide an improved pneumatic feeding means for a rock drill and having improved feed controlling means for regulating the feeding pressure. Another object is to 10 provide an improved pneumatic feeding means for a rock drill whereby a feed of comparatively great length is obtained by means of a relatively compact structure and having improved transmission connections between the power feeding piston and the drill whereby such compactness is possible, and improved fluid sealing means associated with said transmission connections whereby fluid leakage from the feeding cylinder is reduced to a minimum; the improved sealing 15 means cooperating with elements of the drill guiding means. Still another object is to provide improved flexible, force transmitting means between the power feeding element and the drill, and with which the improved fluid sealing means 20 is associated, whereby leakage of fluid from the feed cylinder past the flexible means is substantially eliminated. A further object is to provide an improved tower mounted rock drilling mechanism, supported by a wheeled carriage and having improved drill supporting and guiding means and improved means for feeding the drill. These and other objects and advantages of the 25 invention will, however, hereinafter more fully appear.

30 In the accompanying drawings there is shown, for purposes of illustration, one form which the invention may assume in practice.

In these drawings,—

Fig. 1 is a front elevational view of the illustrative embodiment of the improved rock drilling mechanism.

Fig. 2 is a side elevational view of the drilling mechanism shown in Fig. 1.

Fig. 3 is a cross sectional view taken on line 3—3 of Fig. 2.

Fig. 4 is a cross sectional view taken on line 4—4 of Fig. 2.

Fig. 5 is a detail sectional view taken on line 5—5 of Fig. 2.

Fig. 6 is a central, longitudinally extending,

vertical sectional view taken through the improved drill feeding and guiding structure.

Fig. 7 is a longitudinally extending, vertical sectional view taken substantially on line 7—7 of Fig. 6.

Fig. 8 is a detail sectional view with parts in elevation, showing the improved feed control means.

Fig. 9 is a horizontal sectional view taken on line 9—9 of Fig. 8.

Figs. 10, 11, 12 and 13 are detail sectional views taken on lines 10—10, 11—11, 12—12, and 13—13, respectively, of Fig. 8.

As shown in the drawings, the improved rock drilling mechanism is of the tower mounted, self-feeding type, particularly designed for use in quarry work, although it will be evident that the improved structure constituting the features of this invention may be incorporated in drills of various other types.

The drilling mechanism disclosed herein comprises a wheeled carriage 1 having a tower support and guide, herein in the form of a standard 2, mounted thereon, and on which a rock drill 3 is supported and guided in an improved manner. The wheeled carriage 1 comprises a frame 4, herein generally triangular in shape, supported on an axle 5 for the carriage wheels 6 and having an adjustable ground engaging supporting leg 7 and a suitable draft connection 8 whereby the entire drilling unit may be towed to different locations.

Supported on the carriage frame 4 and superimposed on the wheel axle is a horizontal plate 9 having spaced parallel bores 10, 10 for receiving the lower portions of parallel vertically arranged guide members 11, 11 of tubular form. The upper portions of these parallel tubular members are similarly received within spaced parallel bores 12, 12 formed in a top plate 13. These tubular members are, as disclosed herein, secured within the bores in the plates 9 and 13 by releasable set screws threaded within the plates and engaging the tubular members. Arranged parallel with the tubular members 11, 11, with its axis lying in a vertical plane midway between the tubular members but offset rearwardly therefrom, is a vertically arranged tubular member 14, herein the feeding cylinder of the pneumatic drill feeding means, this feeding cylinder extending coaxially with the members 11 and secured, as by welding or otherwise, to brackets formed integral with the plates 9 and 13. The elements 11 and 14 may be suitably braced with respect to the wheeled carriage, as by suitable brace rods ex-

tending between certain of the elements and the carriage frame. It will thus be seen that the elements 11 and 14 cooperate to form a tower mounting or standard on which the rock drill is supported and guided.

The rock drill 3 is herein of the pressure fluid actuated, hammer type of a standard design, and is detachably mounted on a supporting and guiding frame 15, the latter having formed along its lateral edges concave guiding surfaces 16, 16 slidably engaging with the inner curved sides of the exterior surfaces of the parallel tubular members 11, 11. The rock drill is detachably secured to the frame 15 by means of a transverse holding bolt 17 passing through an opening formed in the back head of the drill, and by clamping bolts 18, 18 engaging with the usual drill side rods, the drill being readily detachable from the guiding frame 15 upon release of the holding elements 17 and 18. The rock drill has a usual throttle valve member 19 operated by a handle 20.

Arranged within the cylinder 21 of the rock drill is a usual hammer piston, not shown, actuated by pressure fluid, for percussively actuating a usual rock drill steel 22 supported in a usual manner within the front chuck housing 23 of the drill, there being provided suitable steel retainer means 24 for maintaining the drill steel in operative position within the drill chuck. For guiding the drill steel 22 during starting of a hole, there is provided a steel centralizer comprising cooperating guide members 25, 25 supported on the bottom plate 9 and pivotally mounted on the lower portions of the tubular members 11, 11; and these members, when swung inwardly into their steel guiding position with the guiding portions 26 thereof embracing the drill steel, are held in such relation by means of a U-shaped holding element 27 engaging the outer sides of the members 25 in the manner shown in Fig. 5. The guiding elements of the centralizer may be readily released simply by withdrawing the element 27 from its holding position and swinging the guiding elements 25 laterally out of guiding relation with the drill steel.

Now referring to the improved feeding mechanism, and more particularly to the improved flexible transmission connections and their associated fluid sealing means, it will be observed that contained in the feeding cylinder 14 and reciprocable longitudinally in either direction relative thereto under the action of pressure fluid, is a feeding piston 28, while reciprocably mounted within the bores of the tubular members 11 are sealing elements, herein in the form of pistons 29 and 30. The feed piston 28 comprises a body element 31 having a central flange against which there are secured, as by clamping elements 32, suitable cup packings 33, the elements 32 being held in position on the piston body by means of holding nuts 34 threaded on the opposite sides of the body element. Threadedly secured within the opposite ends of the body element 31 of the piston are adjustable eye-bolt members 35 connected to the adjacent ends of flexible transmission elements 36 and 37, each in the form of a roller chain of the block type. As shown in Fig. 6, these roller chain sections are connected to the opposite sides of the feed piston, and the other ends of these chains are adjustably connected at 38 each to a body element 39 of the seal pistons 29 and 30.

As shown in Figs. 6 and 7, the upper end of one of the tubular members 11 and the lower end of the other tubular member are reversely bent, 75 at 40 and 41, respectively, in U-shaped form,

and the reversely bent portions of these members each project within a bore 42 formed in a head 43 of the feed cylinder, and each is held in sealed relation therein by means of a packing 44 held under compression in engagement with the exterior periphery of the tubular member by an adjustable plug 45 threaded within the cylinder head. The chain sections 36 and 37 extend in opposite directions upwardly and downwardly through the ends of the feed cylinder, and the upper chain section 36 is guided by the rollers thereof on the inner curved surface 46 of the upper bent portion 40 of the tubular member 11, and extends through the tubular member 11 into connection with the sealing piston 30, while the lower chain section 37 extends in a similar manner about the bottom bent portion 41 of the other tubular member 11 and through this member into connection, at 38, with the other sealing piston 29. Each of the sealing pistons 29 and 30 comprises a head 47 formed on the body element 39, and the piston body element has threadedly secured thereto an adjustable member 48 between which and the head 47 there is compressed suitable packing material 49. Adjustably threadedly engaged at 50 within the top of the sealing piston 29 is a member 51 secured to the adjacent end of a flexible transmission element 52, herein in the form of a cable or wire rope and this flexible element extends upwardly through the tubular member 11 and out through the open top of this tubular member, in the manner shown in Fig. 6, the cable passing around a pulley 53 journaled on a shaft 54 carried by a bracket 55 secured to the top plate 13. This cable passes from this pulley 53 and extends downwardly midway between the tubular members 11, 11 in a direction parallel therewith, and is secured in a suitable manner to an adjustable member 56 in turn secured by a nut at 57 within the rear portion of the guide frame 15 of the drill. Adjustably threadedly secured within the bottom of the other sealing piston 30 is a member 58 having secured thereto the adjacent end of a wire rope or cable 59, similar to the cable 52 and extending in a similar manner downwardly through the tubular member 11 and out through the open lower end of the latter and around a guide pulley 60 journaled on a shaft 61 carried by a bracket 62 secured to the bottom plate 9. This cable extends from the pulley 60 upwardly midway between the members 11, 11, in a direction parallel therewith, and is secured within a threaded member 63 adjustably secured by a nut, as at 64, within the forward portion of the drill guiding frame 15. The adjusting members 56 and 63 are secured to the ends of the wire ropes by pressing or otherwise, and by adjustment of these members the ropes and chain are maintained under the desired tautness. It will thus be seen that the lower end of the feed cylinder, at the lower side of the feed piston, opens directly within the tubular member 11 within which the sealing piston 29 is mounted, and the upper end of the feed cylinder, at the upper side of the feed piston, opens directly into the tubular member within which the sealing piston 30 is reciprocably mounted; while the tubular members, at the other sides of the sealing pistons, open out directly to atmosphere, and these sealing pistons prevent substantial leakage of fluid from the opposite ends of the feed cylinder, through the tubular members, past the sealing pistons.

Now referring to the improved means for con-

trolling the flow of pressure fluid to the feeding means to regulate the feeding pressure, it will be noted that secured in a suitable manner, as by welding, to the rear side of the feed cylinder 5 is a valve box 66 having a conical valve bore 67 in which is rotatably mounted a controlling valve 68 of conical shape. Formed on the valve is a shank 69 having secured thereto a handle 70. Secured within the valve box is an air inlet pipe 10 71 which leads to any suitable source of pressure fluid supply; and pressure fluid is conducted from this pipe through a passage 72 communicating with the internal valve chamber at the inner end of the valve. The valve is made hollow at 73, 15 and communicating with the hollow portion 73 is an axial bore 74 extending through the valve shank. The walls of the valve are perforated by aligned ports 75 communicating with the hollow interior 73 of the valve for connecting a passage 76 with the pressure fluid supply; and this passage is connected, by a connection 77 secured within the valve box, to a flexible hose connection 78, through which pressure fluid is supplied to the inlet connection 79 of the throttle valve 19 20 of the rock drill 3. Formed in different transverse planes on the exterior periphery of the valve are circumferentially extending grooves 80, 81, 82 and 83, the grooves 80 and 81 communicating through the bore 74 with the fluid supply, 25 through passages 84 and 85. Formed in the valve box and communicating with the valve bore are passages 86 and 87; and these passages are connected by suitable conduits, such as pipe connections 88 and 89 respectively, to the upper and 30 lower ends of the feed cylinder, the passage 89 constituting a forward feed passage and the passage 87 constituting a reverse feed passage. Also formed in the valve box for connecting the valve bore to atmosphere, are vent passages 90 and 91. 35 For controlling the flow of pressure fluid from the hollow interior 73 of the valve to the axial bore 74, there is reciprocably mounted in the bore 74 a plunger valve 92 having a suitable operating push button 93 mounted within the valve handle 70, and this plunger valve has formed on its inner face a valve portion 94 adapted to seat on a valve seat 95. When the valve 92 is pushed inwardly to bring the same into seated position on the seat 95, flow of pressure fluid 40 through the bore 74 to the forward and reverse feed passages is cut off, and by varying the position of the valve the flow of feeding pressure fluid may be correspondingly varied. The valve and push button are normally held in their released position by the pressure fluid acting on the inner end of the valve.

Means is provided, associated with the control valve mechanism, for automatically regulating the feeding pressure, and this automatic means 45 comprises a ball valve 97 held on its seat 98, in a position closing the passage 86, by a coiled spring 99. The tension of the spring 99 is adjustable by a follower member 100 threaded within a bushing 101, in turn threadedly engaged within the valve box; and this follower member 100 is provided with a suitable operating handle 102. By regulating the tension of the spring 99, the flow of pressure fluid to the forward feed passage 50 may be regulated as desired, so that any desired forward feeding pressure within the feed cylinder may be attained.

The operation of the improved drilling mechanism will be clearly apparent from the description given. When the control valve 68 is rotated into 55 a position to bring the groove 80 into communica-

tion with the forward feed passage 86, pressure fluid may flow through the valve, through the passage 86, past the automatic regulating valve 97, and through the pipe connection 88 to the upper end of the feed cylinder, the pressure fluid flowing to the upper end of the feed cylinder acting on the upper face of the feed piston to effect movement of the latter downwardly within the feed cylinder. Downward movement of the feed piston is transmitted through the chain section 36 and the cable section 59 to the guide frame of the rock drill, so that as the feed piston moves downwardly within its cylinder the rock drill moves in the same direction forwardly along its guides. When the control valve is in this position, the lower end of the feed cylinder at the lower side of the feed piston is vented to atmosphere through the passage 87, groove 82 and vent passage 90. The supply of feeding pressure to effect forward feed may be regulated as desired 60 by regulating the tension of the spring 99 of the automatic regulating valve. Forward feed may be manually regulated simply by controlling the position of the plunger valve 92 to regulate the flow of pressure fluid through the passage 85. Reverse feed may be effected by rotating the control valve 68 to a position wherein the groove 81 communicates with the reverse feed passage 87, and pressure fluid then flows through the passage 85, groove 81, passage 87 and pipe connection 89, 65 to the lower end of the feed cylinder, the pressure fluid flowing to the lower end of the feed cylinder acting on the lower face of the feed piston to effect movement of the latter upwardly within the cylinder. This upward movement of the feed piston is transmitted to the rock drill through the lower chain section 37 and the cable section 52 connected to the rock drill guide, to move the latter rearwardly along its guides. During rearward movement of the feed piston, the upper end 70 of the feed cylinder is connected to exhaust through the groove 83 and vent passage 91, the venting fluid by-passing around the automatic control valve 97. The reverse feeding movement of the piston may be controlled by adjusting the 75 position of the plunger valve 92 to regulate the flow of pressure fluid through the passage 85. Of course as the feed piston reciprocates in the feed cylinder the sealing pistons reciprocates with the sealing cylinders formed by the tubular guide 80 members, the sealing pistons moving in a direction opposite from the direction of movement of the feed piston, so that the flexible elements are at all times maintained sealed with respect to the feed cylinder.

As a result of this invention it will be noted that an improved rock drill feeding mechanism is provided, wherein a relatively long feed is attained without materially increasing the over-all dimensions of the feeding and guiding structure. It 85 will further be noted that an improved rock drill feeding mechanism of the pneumatic type is provided, having improved flexible transmission means between the power feeding element and the rock drill, and improved sealing means associated with the transmission means whereby fluid leakage is reduced to a minimum. It will still further be evident that by the provision of the improved feeding structure, the rock drill is supported and guided in an improved manner, and 90 that by associating the feeding elements with the guiding structure the feeding means is rendered extremely simple in design, and by its simplicity results in a feeding structure which is more rugged in design and inexpensive to man- 95

ufacture. These and other uses and advantages of the improved drilling mechanism will be clearly apparent to those skilled in the art.

While there is in this application specifically 5 described one form which the invention may assume in practice, it will be understood that this form is shown for purposes of illustration only, and that the invention may be modified and embodied in various other forms without departing 10 from its spirit or the scope of the appended claims.

What I claim as new and desire to secure by Letters Patent is:

1. In a rock drilling mechanism, a feed cylinder, 15 a feed piston reciprocable therein, tubular guide members communicating respectively with the opposite ends of said feed cylinder, a rock drill guided on said members, sealing pistons reciprocable in said tubular members, flexible transmission elements connecting said feed piston to 20 said sealing pistons, and flexible transmission elements connecting said sealing pistons with the rock drill.

2. In a rock drilling mechanism, a feed cylinder, 25 parallel tubular guide members parallel with said feed cylinder and communicating respectively with the opposite ends of said feed cylinder, elements connecting the opposite ends of said members and cylinder in rigid spaced relation, a 30 rock drill guided on said tubular members therebetween, a feed piston reciprocable in said feed cylinder, sealing pistons reciprocable in said tubular members, flexible transmission means connecting said feed piston to said sealing pistons, 35 and flexible transmission means connecting said sealing pistons to the rock drill.

3. In a rock drilling mechanism, parallel tubular elements, a feed cylinder parallel with said elements, one of said tubular elements having a 40 reversely bent portion communicating with one end of the feed cylinder and the other element having a reversely bent portion communicating with the opposite end of said feed cylinder, a feed piston reciprocable in said feed cylinder, a rock 45 drill guided for movement longitudinally of said tubular elements, flexible transmission means connected to the opposite ends of said feed piston and extending through the opposite ends of said feed cylinder and said tubular elements into 50 connection with said rock drill, and sealing means carried by said flexible means and engaging with a sealing action the inner walls of the tubular elements for preventing leakage of pressure fluid from the opposite ends of said feed cylinder 55 through said tubular elements.

4. In a rock drilling mechanism, parallel tubular members, a rock drill guided on said tubular members for movement longitudinally thereof, a feed cylinder parallel with said tubular members, one of said tubular members having a reversely bent portion communicating with one end of said feed cylinder and the other tubular member having a reversely bent portion communicating with the opposite end of said feed cylinder, a feed piston reciprocable in said feed cylinder, sealing pistons reciprocable within said tubular members, flexible elements connected to the opposite sides of said feed piston and extending outwardly through the ends of said feed cylinder and said tubular members into connection with said sealing pistons, and flexible elements connected to said sealing pistons and extending into connection with said rock drill.

5. In a rock drilling mechanism, parallel tubu-

lar members, a rock drill guided on said tubular members for movement longitudinally thereof, a feed cylinder parallel with said tubular members, one of said tubular members having a reversely bent portion communicating with one end of said feed cylinder and the other tubular member having a reversely bent portion communicating with the opposite end of said feed cylinder, a feed piston reciprocable in said feed cylinder, sealing pistons reciprocable within said tubular members, 10 flexible elements connected to the opposite sides of said feed piston and extending outwardly through the ends of said feed cylinder and said tubular members into connection with said sealing pistons, flexible elements connected to said sealing pistons and extending into connection with said rock drill, and guiding means mounted at the opposite ends of said tubular members for guiding said last mentioned flexible elements, said latter flexible elements extending outwardly 20 through said tubular members and around said guiding means and then inwardly toward one another into connection with said rock drill.

6. In a rock drilling mechanism, a feed cylinder, 25 tubular cylinders communicating with the opposite ends of said feed cylinder, a feed piston reciprocable in said feed cylinder, sealing piston means reciprocable in said tubular cylinder respectively, flexible connections for connecting the opposite sides of said feed piston to said sealing piston means, a rock drill guided on certain of said cylinders for movement longitudinally thereof, and flexible means for connecting said sealing piston means with said rock drill.

7. In a rock drilling mechanism, parallel tubular guiding elements, a feed cylinder parallel with said elements, one of said tubular elements having a reversely bent portion communicating with one end of the feed cylinder and the other tubular element having a reversely bent portion communicating with the opposite end of said feed cylinder, a rock drill guided on said tubular guiding elements for movement therealong, a feed piston reciprocable in said feed cylinder, sealing pistons reciprocable in said tubular elements, and flexible transmission means connected to the opposite ends of said feed piston and to said sealing pistons and extending through the opposite ends of said feed cylinder and said tubular elements into connection with said rock drill.

8. In a rock drilling mechanism, drill guiding means including a tubular drill guide member, a feed cylinder parallel with said guide member, a feed piston reciprocable in said feed cylinder, a rock drill guided on said guiding means, a sealing piston reciprocable in said tubular guide member, and flexible transmission elements respectively connecting said feed piston to said drill and said sealing piston to said feed piston.

9. In a rock drilling mechanism, a rock drill and a supporting, guiding and feeding structure for said rock drill embodying parallel tubular members, and a feed cylinder parallel with said tubular members, said tubular members communicating respectively with the opposite ends of said feed cylinder, a feed piston reciprocable in said feed cylinder, sealing pistons reciprocable in said tubular members, and means connecting said feed piston, said drill, and said sealing pistons.

10. In a rock drilling mechanism, a rock drill and a supporting, guiding and feeding structure on which said rock drill is guided for feeding movement and embodying a feed cylinder and a tubular sealing cylinder communicating with said

feed cylinder, a feed piston reciprocable in said feed cylinder, a sealing piston reciprocable in said sealing cylinder, and flexible transmission means connecting said feed piston to said rock drill 5 and said sealing piston to said feed piston.

11. In a rock drilling mechanism, a feed cylinder, a pair of guiding cylinders extending substantially co-extensive and parallel with said feed cylinder, one end of one guiding cylinder communicating with one end of said feed cylinder and the opposite end of said other guiding cylinder communicating with the opposite end of said feed cylinder, a rock drill guided on said parallel guiding cylinders for movement longitudinally 10 therealong, a feed piston reciprocable in said feed cylinder, sealing pistons reciprocable in said guiding cylinders respectively, flexible connections within said feeding and guiding cylinders for connecting said sealing pistons to said feed piston, 15 and flexible connections extending within said guiding cylinders for connecting said sealing pistons to said rock drill.

12. In a rock drilling mechanism, a feed cylinder, a pair of guiding cylinders extending substantially co-extensive and parallel with said feed cylinder, one end of one guiding cylinder communicating with one end of said feed cylinder and the opposite end of said other guiding cylinder communicating with the opposite end of said feed cylinder, a rock drill guided on said parallel guiding cylinders for movement longitudinally therealong, a feed piston reciprocable in said feed cylinder, sealing pistons reciprocable in said guiding cylinders respectively, flexible connections within 30 said feeding and guiding cylinders for connecting said sealing pistons to said feed piston, flexible connections extending within said guiding cylinders for connecting said sealing pistons to said rock drill, and guiding means at the opposite 35 ends of said cylinders for guiding said flexible connections.

13. In a rock drilling mechanism, a feed cylinder, a pair of guiding cylinders extending substantially co-extensive and parallel with said feed cylinder, one end of one guiding cylinder being reversely bent and communicating with one end of said feed cylinder and the opposite end of said other guiding cylinder being reversely bent and communicating with the opposite end of said feed 40 cylinder, a rock drill guided on said parallel guiding cylinders for movement longitudinally therealong, a feed piston reciprocable in said feed cylinder, sealing pistons reciprocable in said guiding cylinders respectively, flexible connections within 45

said feeding and guiding cylinders and extending around said reversely bent portions of said guiding cylinders for connecting said sealing pistons to said feed piston, and flexible connections extending within said guiding cylinders for connecting said sealing pistons to said rock drill. 5

14. In a rock drilling mechanism, a feed cylinder, a pair of guiding cylinders extending substantially co-extensive and parallel with said feed cylinder, one end of one guiding cylinder being reversely bent and communicating with one end of said feed cylinder and the opposite end of said other guiding cylinder being reversely bent and communicating with the opposite end of said feed cylinder, a rock drill guided on said parallel 10 guiding cylinders for movement longitudinally therealong, a feed piston reciprocable in said feed cylinder, sealing pistons reciprocable in said guiding cylinders respectively, flexible connections 15 within said feeding and guiding cylinders and extending around said reversely bent portions of said guiding cylinders for connecting said sealing pistons to said feed piston, and flexible connections extending within said guiding cylinders for connecting said sealing pistons to 20 said rock drill, said reversely bent portions of said guiding cylinders providing guiding means for said first mentioned flexible connections. 25

15. In a rock drilling mechanism, a feed cylinder, a pair of guiding cylinders extending substantially co-extensive and parallel with said feed cylinder, one end of one guiding cylinder being reversely bent and communicating with one end of said feed cylinder and the opposite end of said other guiding cylinder being reversely bent and 30 communicating with the opposite end of said feed cylinder, a rock drill guided on said parallel guiding cylinders for movement longitudinally therealong, a feed piston reciprocable in said feed cylinder, sealing pistons reciprocable in said guiding 35 cylinders respectively, flexible connections within said feeding and guiding cylinders and extending around said reversely bent portions of said guiding cylinders for connecting said sealing pistons to said feed piston, flexible connections extending within said guiding cylinders for connecting said sealing pistons to said rock drill, said reversely bent portions of said guiding cylinders providing guiding means for said first mentioned 40 flexible connections, and guiding pulleys at the 45 opposite ends of said cylinders for guiding said second mentioned flexible connections. 50

MERVIN CHESTER HUFFMAN.
